UNITED STATES PATENT OFFICE.

CHARLES E. JOHNSON, OF NEW YORK, N. Y.

CIGAR CASE AND CUTTER.

1,249,105.

Specification of Letters Patent. Patented Dec. 4, 1917.

Application filed November 10, 1916. Serial No. 130,638.

To all whom it may concern:

Be it known that I, CHARLES E. JOHNSON, a citizen of the United States, residing at New York, in the county of New York and State of New York, have invented new and useful Improvements in Cigar Cases and Cutters, of which the following is a specification.

This invention relates to a combined cigar case and cutter.

The primary object of the present invention is to produce a cigar case, by means of which cigars may be conveniently carried in the pocket without liability of breakage and to provide within the case means for cutting the end off of the cigars as is the usual custom.

A further object of the invention is the provision of a case, containing means for yieldingly holding therein a plurality of cigars, the cigars being held in a manner to permit the ends being cut therefrom, and dropped through openings provided in the casing.

A still further object of the invention is to provide a case of a convenient size having housed therein a cutter by means of which the smoker may remove the ends from cigars in a convenient and sanitary manner, obviating the necessity of using a common cigar cutter and thereby avoiding the danger of contraction of infectious or contagious diseases arising therefrom.

With the above and other objects in view the invention consists of a cigar case provided at one end with a cylinder, a plurality of openings in the said cylinder, the said openings being surrounded with thimbles adapted to receive the ends of the cigars, a cutter movable across these openings and a yieldingly mounted spring actuated plate adapted to engage the opposite ends of the cigars in order to retain them in position.

In the drawings;

Figure 1 is a perspective view of the cigar case constructed in accordance with the present invention, in closed position;

Fig. 2 is a vertical longitudinal sectional view of the same showing the cigars therein by dotted lines;

Fig. 3 is a vertical transverse sectional view of the same;

Fig. 4 is a horizontal sectional view;

Fig. 5 is a detail perspective view of the thimbles removed from the case and illus-

trating the manner of forming the same from a single piece of material and showing the connections between each of the thimbles;

Fig. 6 is a detail perspective view of the follower plate; and

Fig. 7 is a detail vertical longitudinal sectional view of the lower portion of the case showing the modified form of the cutter.

Referring in detail to the drawings, the improved case which is preferably constructed of metal, is shown at 1. It comprises a back, 2 a front 3 and curved side walls 4 and end walls 5 and 6 respectively. The front 3 is formed with an opening including practically its entire area and this opening is adapted to be closed by a hinged door 7, which is held in position by means of a catch 8 of any suitable construction. The case is of a size to be conveniently carried in the pocket and is shown in the drawings as adapted to carry four cigars of the usual size, although it is of course obvious that it may be made to accommodate various numbers.

Formed within the end 6 of the casing is a cylinder 9, the said cylinder being slightly shorter in length than the width of the case to provide inset portions 10 at each end thereof. Formed in the cylinder and communicating with the interior of the case are a plurality of openings 11, being beveled as at 12 for the purpose of guiding the cigar ends therethrough as will be presently apparent. Surrounding each of the openings 11 are conical thimbles 13, the lower reduced ends of these thimbles being of a diameter slightly greater than the openings 11. As will be seen from Fig. 5 of the drawings these thimbles are formed from a single piece of material stamped or cut in the proper form and shape so as to provide a plurality of thimbles joined together at their upper or larger ends by means of a connecting strap 14 as will be readily understood. This strap aids in preventing any tendency of the thimbles to become disarranged or disengaged from the cylinder as might be the case were each thimble separately secured and having no connection with one another.

The thimbles just described are designed to form a guiding and holding means for the ends of the cigars to be acted upon by the cutter, and in order to securely hold the

100
105
110

cigars therein, the case is further provided with a spring pressed follower plate 15. This plate is preferably arcuate in cross section and has formed at each end a dependent arm 16, provided with a right angular extension 17, which has therein an opening 18. Secured within the case at each side thereof is a pair of guide rods 19, secured at their ends within the case in any suitable manner, the said rods being adapted to be passed through the openings 18 to provide guiding means for the follower plate 15. In order to properly position this plate to provide for the positioning of the cigars and to accommodate cigars of various lengths there is attached to each of the arms 16 a coil spring 20, the other end of this spring being secured within the case near the top. This arrangement provides for the raising 20 of the plate to permit of the placing of the cigars within the thimbles, the spring acting to force the plate into a yielding engagement with the cigars and to hold them in position.

25 Mounted within the cylinder 9 is a shaft 21 which has its bearings in each end of the cylinder, and is provided upon one end with a securing nut 22 and upon its opposite end with a knurled disk 23, by means of 30 which it may be rotated. Secured upon the shaft 21 is a spiral cutter 24 comprising a plurality of convolutions, one of which is adapted to operate across the openings 11 for the purpose of cutting the end from the cigar. This cutter could be made in various ways, the one shown being formed of a continuous spiral strip provided with attaching arms at each end and at intermediate points thereof by means of which it is secured upon 35 the shaft 21. After the cigars have been placed within the holder a partial rotation of the disk 23 will cause the spiral cutter to travel across the openings 11 and cut the ends from the cigars, which are dropped 40 into the bottom of the cylinder 9, from which they may be removed by means of the openings 6.

In Fig. 7 there is illustrated a modified form of the cutter, which consists of a blade 25 provided with beveled openings 26 adapted to normally register with the openings 11. Upon the outer end of this blade is a push button 27 and mounted upon this blade between the push button 27 and the casing is a spring 28 for the purpose of returning the blade to its normal position. In order to hold the blade 25 in position beneath the openings 11, there is provided a guide plate 30 having therein openings 31 which register 35 with the openings 11, so that the cigar end

may be inserted therethrough and the blade actuated to remove the said end.

From the foregoing description taken in connection with the accompanying drawings it is believed that the construction and operation of the invention will be sufficiently clear and that a further explanation is unnecessary.

The right is reserved to make such changes in the form and proportion of the invention as may be within the scope of the appended claims.

Having described the invention what is claimed is;

1. A combined cigar case and cutter comprising a receptacle, a transverse partition therein provided with a plurality of openings adapted to receive the ends of cigars, a shaft rotatably mounted within said receptacle, a spiral cutter secured to and surrounding said shaft, said cutter comprising a plurality of convolutions forming a continuous cutting element adapted to move across said openings to cut the ends from the cigars and a follower plate yieldingly engaging the opposite ends of the cigars to hold them in position within said openings.

2. A combined cigar case and cutter comprising a receptacle, a transverse partition therein provided with a plurality of openings adapted to receive the ends of cigars, thimbles arranged above each of said openings, straps connecting each of said thimbles, a cutting element mounted for movement across said openings and a follower plate yieldingly engaging the opposite ends of the cigars.

3. A combined cigar case and cutter comprising a receptacle, means within said receptacle for yieldingly holding a plurality of cigars and a rotatably mounted spiral provided with a cutting edge and located within said receptacle in juxtaposition to the cigar holding means and adapted to be rotated to cut the ends from the cigars.

4. A combined cigar case and cutter comprising a receptacle, a transverse partition therein provided with a plurality of openings adapted to receive the ends of cigars, thimbles arranged above each of the openings, said thimbles being cut from a single piece of material and shaped to form a plurality of cigar receiving sockets and connecting straps, a cutting element mounted for movement across said openings and a follower plate engaging the opposite ends of the cigars.

In testimony whereof I affix my signature.

CHARLES E. JOHNSON.
